UNITED STATES PATENT OFFICE

1,992,861

SERVING APPARATUS

James Demos, Jacksonville, Fla.

Application October 26, 1932, Serial No. 639,713

2 Claims. (Cl. 186—1)

This invention relates to apparatus designed primarily for use in lunch rooms and restaurants whereby food can be conveyed from the kitchen or other point of supply, to places accessible to customers who, while standing still, can make selections from the displayed food passing before them.

A further object is to provide a conveying means for keeping the food at desired temperatures while in motion.

A still further object is to provide apparatus which can be installed readily as a unit and will operate quietly and efficiently both to transport the foods to the customers and to return soiled and empty dishes to the kitchen or other desired place.

With the foregoing and other objects in view which will appear as the description proceeds the invention resides in the combination and arrangement of parts and in the details of construction hereinafter described and claimed it being understood that changes in the precise embodiment of the invention herein disclosed may be made within the scope of what is claimed without departing from the spirit of the invention.

In the accompanying drawings the preferred form of the invention has been shown.

In said drawings

30 Figure 1 is a front elevation, partly in plan and partly in section, of the apparatus, an intermediate portion being broken away.

Figure 2 is a section on line 2—2, Figure 1.

35 Figure 3 is an enlarged central vertical transverse section.

Referring to the figures by characters of reference, 1 designates a housing of any desired proportions adapted to extend from a kitchen wall or partition.

40 It is located where it is accessible readily by customers. The end portions of the housing can be closed by front panels 2 for the purpose of concealing the end mechanism of the conveyor and the lower portion of the space between these panels can also be closed by a front panel 3. The back of the housing can be placed against a wall W but usually the housing will extend into the room so that customers can stand at both sides.

50 Erected in the end portions of the housing and also at intermediate points if found necessary or desirable, are standards each consisting preferably of opposed angle members 4 suitably connected at their lower ends to transverse base strips 5 and at their upper ends to top beams 6.

The top 7 of the housing can be supported by these latter beams.

Cross arms 8, 9 and 10 are attached to the standards. The lower arms 8 support an angle strip 11 which forms a continuous rail having an inner upstanding continuous flange 12. Those portions of the rail and its flange in the end portions of the housing are semicircular and concentric with vertical shafts 13 and 14 located in the housing. Shaft 13 is journaled in upper and lower brackets 15 carried by the adjacent standard members 4 while shaft 14 is journaled in slides boxes 16 in upper and lower brackets 17 carried by the standard members 4 at the other end of the housing. These boxes can be 15 adjusted by screws 18, as will be obvious, for the purpose of shifting shaft 14 toward or from shaft 13.

An inner rail 19 is surrounded by and parallel with the rail flange 12 and cooperates therewith to form a continuous track or runway. This rail is partly overhung by a continuous inverted angle rail 20 parallel with rail 19 and secured to standard members 4. The bottom surface of the top portion of the rail 20 constitutes a bearing 25 surface as hereinafter explained.

Extending over the rails 11, 19 and 20 is an endless belt in the form of a chain 21 or the like mounted on wheels or sprockets 22 secured to shafts 13 and 14. Separate trays extend outwardly over the rails from the chain or belt as shown at 23 and each has a flange 24 at its inner end attached at its center to the belt or chain 21.

Connected to the bottom of each tray is a pair 35 of rollers or wheels 25 which travel on rail 11 and additional wheels or rollers 26 are attached to the inner sides of the trays and travel along the bottom surface of rail 20. These wheels 25 and 26 cooperate to hold the trays substantially horizontal as they are drawn along the rails by the belts 21. Another set of wheels 26' is carried by the trays for travel between flange 12 and rail 19 and act to guide the trays during their travel.

40 A second endless belt or chain 21 is located above arms 9 and driven by sprockets 22. This belt also has a series of trays 27 secured thereto and extending over another set of rails 11, 19 and 20 such as already described, there being 50 wheels 25, 26 and 26' cooperating therewith.

A third series of trays 28 is extended over an upper set of rails 11, 19 and 20 on the upper arms 10, these trays being attached to an upper endless belt or chain 21 driven by sprockets 22 on 55

shafts 13 and 14. These trays also have wheels 25, 26 and 26' cooperating with the rails.

The arms 9 have depending shield plates 29 overhanging the adjacent trays 23 so as to conceal the central supporting and conveying structure.

Located beneath the trays 28 are arms 30 supporting a metal pan 31 extending under all portions of the upper series of trays 28 and this pan has a layer of insulation indicated at 31'. Between the insulation and the trays 28 are steam coils or pipes 32 for heating trays 28 and the articles carried thereby.

Pipes 33 for conducting a refrigerant are located above trays 27 and beneath pan 30. Downwardly and outwardly inclined insulating panels 34 are located under and back of the pipes 33 and are adapted to drain into gutters 35 having drain gutters 36 or the like.

Shield panels 37 are supported by arms 6 so as to conceal the central supporting and conveying mechanism of the apparatus.

A shaft 38 driven by any suitable means not shown, is located back of the panel 3 and is adapted to transmit motion through chain and sprocket mechanism 39 or the like to shaft 13.

In practice the shaft 38 is operated and this will cause shaft 13 and all of the chains 21 to move continuously at a desired speed. Consequently the three movable shelves formed by trays 23, 27 and 28 respectively will be set in motion and said trays will move through partition P, along housing 1 in full view of the customers, and then return to the kitchen by traveling back of the shields 29 and 37 and the insulation 34 which also constitutes a shield.

Hot foods and beverages are placed on the upper movable shelf consisting of trays 28 while foods and beverages to be kept cold are placed on the middle shelf. The lower shelf is used for the return of used dishes. As the food passes on display the customers can select and remove their choices while unused portions will continue back to the kitchen and thence again on display.

Empty trays can be easily replenished as they travel through the kitchen.

With apparatus of the kind described all customers lined up before the shelves can be served simultaneously and there is no delay due to slowness of a customer in making selections.

While the apparatus is especially suited for use in restaurants, it can also be employed advantageously in grocery stores, delicatessen stores, and other places where packages of suitable size are displayed.

What is claimed is:

1. Serving apparatus including superposed endless belts, upper and lower series of trays connected at their inner ends to the respective belts, said trays being arranged close together so as to constitute substantially continuous top and bottom closures of a food containing space, stationary heat exchange means within said space, rails beneath the inner end portions of the trays of the respective series, and rollers carried by each tray adjacent to its inner end and cooperating with the rails to guide the tray during its movement with the belt and to support the tray in a substantially horizontal position during such movement and while subjected to the weight of a load on the unsupported outer end portion thereof.

2. Serving apparatus including superposed endless belts, a series of closely arranged trays connected to each belt, thereby to provide upper and lower closures for a food containing space within the apparatus, a pan within said space substantially closed by the trays of the upper series while moving thereover, stationary heat exchange means within the pan and concealed by the trays thereover, lower stationary heat exchange means below the pan, the trays of the lower series constituting means for substantially preventing downward circulation of air from said lower heat exchange means, and means at the inner end of all the trays for guiding the trays while moving with the belts and for maintaining the trays substantially horizontal while their outer unsupported ends are carrying a load.

JAMES DEMOS.
